UNITED STATES PATENT OFFICE.

THOMAS S. HOMANS, OF HEMPSTEAD, NEW YORK, ASSIGNOR TO INTERNATIONAL TYPE-SETTING MACHINE COMPANY, OF NEW YORK, N. Y., A CORPORATION OF NEW YORK.

TYPOGRAPHICAL MACHINE.

1,156,031.

Specification of Letters Patent.

Patented Oct. 5, 1915.

Application filed February 12, 1915. Serial No. 7,829.

To all whom it may concern:

Be it known that I, THOMAS S. HOMANS, a citizen of the United States, residing at Hempstead, in the county of Nassau and State of New York, have invented new and useful Improvements in Typographical Machines, of which the following is a specification.

The present invention relates to improvements in line casting machines of the linotype class and more especially to those embodying a plurality of magazines any one of which may be placed in operative position as desired and the primary object of the invention is to provide simplified and improved means whereby three or more magazines may be contained in the machine and any one of such magazines may be brought into operative position as desired to deliver the matrices under control of the keyboard and to receive the matrices from the distributor after use.

To these and other ends, the invention consists in certain improvements and combination and arrangements of parts all as will be hereinafter more fully described, the features of novelty being pointed out particularly in the claims at the end of the specification.

In the accompanying drawings: Figure 1 is a side elevation of the upper portion of a machine of the linotype class, embodying magazine shifting means constructed in accordance with the present invention. Fig. 2 is a view similar to Fig. 1 but showing the magazines shifted into a different position. Fig. 3 is a diagrammatic view showing the magazines at an intermediate stage in the shifting operation. Fig. 4 shows the magazines swung bodily to the rear of the machine for removal and Fig. 5 represents a section on the line 5—5 of Fig. 1.

Similar parts are designated by the same reference characters in the several views. The present invention is applicable generally to line casting machines of the class wherein matrices are stored in magazines and are delivered therefrom as desired by manipulation of the keyboard. In the present instance, the invention is shown applied to a machine of the linotype class which is adapted to contain three magazines which are in inclined position and superposed re-

lationship and means is provided for shifting the magazines whereby any one of them can be brought into operative position as may be desired. As shown, 1 designates the upper portion of the main frame of the machine and 2 designates the bracket which supports the distributor. The distributor is shown conventionally as of the construction commonly used on machines of this class, it embodying a combination rail 3 from which the matrices M are suspended and which are fed along this rail by the conveyor screws 4, and 5 designates the magazine entrance which receives the matrices from the distributor and guides them into the appropriate channels of whichever magazine is in use. The magazine entrance is movable to and from operative position in order that it may be shifted clear of the upper ends of the magazines while the latter are being shifted. In the construction shown, the magazine entrance is pivoted on the distributor bracket at 6 and is connected by a link 7 to a handle 8, the latter being within convenient reach of the operator at the front of the machine and is adapted to be manipulated to swing the magazine entrance rearwardly to clear the upper ends of the magazines preparatory to the shifting thereof, as shown in Fig. 2 and to be swung forwardly into the operative position as shown in Fig. 1. The three magazines 9, 10 and 11 are arranged in inclined position and in superposed relation and they are supported on the magazine frames 12, 13 and 14 respectively, the magazine frames being connected at the sides by the upper and lower side plates 15 and 16.

The side plates 15 and 16 supporting the magazines and their frames are carried by a rocker frame 17 which is pivoted on the main frame at 18 and is adapted to swing in a forward and rearward direction to carry the magazines to operative and inoperative positions respectively, as shown in Figs. 1 and 4. The lower or forward ends of the magazines are mounted on a cross shaft 19, this cross shaft being fixed at its ends to collars 20 and said collars are fixed on the inner ends of a pair of stub shafts 21 which stub shafts have hubs 22 which are movable longitudinally in slots 23 formed toward the front of the rocker frame 17. Preferably,

the slots 23 are horizontal when the rocker frame is in operative position. Pinions 24 are fixed to the shafts 21 and coöperate with racks 25 which are formed on or attached to the respective sides of the rocker frame 17.

An operating crank 25 is fixed to one of the shafts 21 and by turning the crank, the pinions 24 will revolve, they being connected to revolve in unison by the shaft 19, and the pinions will in consequence travel longitudinally in the slots 23. The shaft 19, however, which supports the side plates 16 is eccentric to the axis of the pinions during the rotary and longitudinal movement of the pinions, the shaft 19 will describe a cycloidal path and this cycloidal motion will be imparted to the lower or forward ends of the magazines. Preferably, one revolution of the crank serves to position each magazine in operative position.

In the construction shown, the lower ends of the magazines 9, 10 and 11 are provided with escapements 27, 28 and 29 to control the delivery of matrices from the magazines and a set of reeds or escapement actuating rods 20 are mounted to move vertically in the frame 1. As each magazine is brought into operative position, its escapements will be moved into coöperative relation with the reeds 30. The cycloidal movement which is imparted to the lower ends of the magazines during each revolution of the crank 26 operates first to lift the escapements of whatever magazine happens to be in operative position upwardly above the reeds 30, then shifts the escapements laterally above the reeds to carry the escapements of one magazine out of operative relation with the reeds. and the final part of the cycloidal movement causes the escapements of the magazine which is moving into operative position to descend into coöperative relation with the reeds.

In the construction shown in Figs. 1 and 4, the upper ends of the magazines and their frames are guided and supported by pins or rollers 31 which move longitudinally in horizontal slots 32 formed in the upper portion of the rocker frame 17, it being understood that the upper ends of the magazine are guided to successively assume a position in register with the magazine entrance 5.

In the construction shown in Figs. 2 and 3, means is provided for imparting cycloidal movement to the upper and lower portions of the magazines and their frames. In this construction, the upper side plates 15 are supported by a cross shaft 33 which is fixed at its ends to a pair of cranks 34, the latter being located at opposite sides of the magazine frames and are fixed to shafts 35 carrying pinions 36, the pinions coöperating with racks 37 formed on or attached to the upper portion of the rocker frame 17 and hubs or collars on the shafts 35 operate longitudi-

nally in horizontal slots 38 formed in the upper portion of the rocker frame. Links 39 connect the upper shafts 35 and the lower shafts 19. If desired, the racks 37 which control the cycloidal movements for the upper portions of the magazines could be placed at the lower sides of the slots 38 and the crank arms 34 set in parallelism with the crank arms 20, in which case, the magazines would move bodily in a cycloidal path during the shifting of the magazines. In the construction shown, however, the racks 37 are located at the upper sides of the slots 38 and the crank arms 34 are set at substantially opposite angles to the crank arms 20 and, consequently, during the shifting of the magazines, the upper and lower portions of the magazines will describe cycloidal paths but the cycloidal paths will alternate so that when the lower ends of the magazines are rising, the upper ends of the magazines will be falling and vice versa, and in that way the weight of the magazines will be at all times nearly balanced and very little effort will be required to turn the handle.

Fig. 3 illustrates diagrammatically the movements described by the magazines during the shifting operation. In the construction shown, the axis of the shafts 19 and also of the shafts 33, when such are used, are on the pitch line of the respective pinions on these shafts thereby causing these shafts to describe true cycloids, but it will be understood that the shafts may be located either within or outside of the pitch lines of the respective pinions to accomplish the same result without departing from the principle of the invention.

Having described my invention, I claim:

1. In a machine of the linotype class, in combination, a plurality of inclined matrix magazines, a set of underlying escapement actuating devices, and means for moving the magazines to bring any one of them into operative position, said means including a pivotal support for the lower ends of the magazines and guiding means for moving the pivotal support in one or more substantially cycloidal paths.

2. In a machine of the linotype class, in combination a plurality of inclined matrix magazines, a set of underlying escapement actuating devices, a pivot supporting the lower ends of the magazines, and means for moving said pivot in a substantially cycloidal path to bring the desired magazine into operative position.

3. In a machine of the linotype class, in combination, a plurality of inclined matrix magazines, a set of underlying escapement actuating devices, a pivot supporting the lower ends of the magazines, and means for moving said pivot in a plurality of substantially cycloidal paths to bring any one of said magazines into operative position.

4. In a machine of the linotype class, in combination, a plurality of inclined matrix magazines, a set of underlying escapement actuating devices, a frame having a rack thereon, a pinion co-operative with said rack, and a pivot carried by said pinion and supporting the lower ends of the magazines, and operative to move the latter in a plurality of substantially cycloidal paths to bring any

one of the magazines into operative position.

In testimony whereof I have hereunto set my hand in presence of two subscribing witnesses.

THOMAS S. HOMANS.
